UNITED STATES PATENT OFFICE

GEORGE H. GREENHALGH, OF NEWARK, NEW JERSEY, AND ROBERT P. F. LIDDELL, OF NEW YORK, N. Y., ASSIGNEES TO MOTORS IMPROVEMENTS, INC., A CORPORATION OF DELAWARE

PURIFIER FOR CONTAMINATED LIQUIDS

Application filed June 27, 1924. Serial No. 722,667.

Our invention relates to apparatus for purifying contaminated liquids and for separately collecting the pure liquid and the impurities removed therefrom. In describing our invention as particularly applicable to the purification of used lubricating oil such as the oil drained from internal combustion engines, machine tools, and the like, we do not wish to be understood as limiting our invention thereto, since obviously the apparatus may be used with a variety of widely different materials and for many different purposes.

The invention has for its main object the removal of contamination from used oil and other liquids by simple and automatic means.

Other objects of the invention are to provide convenient means for disposing of used oil, for clarifying the same by the removal of foreign matter including dirt, sediment, carbon and minute solid particles; for distilling the same to remove low-boiling diluents, lighter hydrocarbons, water, and other liquid impurities, and to obtain a lubricant of uniform desired viscosity; for regulating the distillation of the oil to obtain a light, or heavy or intermediate grade of finished oil as desired; for carrying on the distillation without injuring the oil and without wasting the valuable diluents removed from the oil; and for accomplishing the above objects automatically and simply in fool proof apparatus, requiring little or no attention, and adapted to start up and operate whenever it is supplied with oil for purification and to stop operating when the supply of oil for purification has given out.

Heretofore it has been a great problem to users of lubricating oil in quantity to know what to do with the used, contaminated and waste oils. The reclaiming of such oils by the expensive and complicated refining apparatus heretofore known has been inefficient and not worth the cost except in cases where sufficient supply of oil was available at all times to keep the apparatus in constant operation. To smaller users the problem of getting rid of such oil has become a serious source of expense and annoyance. Using waste oils sporadically as boiler fuel or the

like is unsatisfactory and generally impracticable. In many localities the disposal of oils in rivers or sewers is prohibited by law. Accumulations of used oils in garages, machine shops, etc. are generally not worth reclaiming by means heretofore known and so are barreled and carted away with resulting loss of the lubricating values and expense of disposal as well.

It is now recognized that lubricating oil does not wear out by use, and that contaminated oil when purified may be as good or better than when it was new. In providing a simple and efficient apparatus for automatically reclaiming and purifying used oils and adapted for efficient use with small and intermittent supply as well as with steady supply up to its full capacity, we have at once provided means for preventing the loss of valuable lubricants and diluents through disposal of the used oils and for avoiding the expense and bother of getting rid of them.

Our invention is particularly adapted for use in garages, machine shops, small factories, and the like, where the supply of used oil is sporadic; and it is designed to operate with little or no attention and without waste.

The foregoing and other advantages of our invention will appear from the following description of an apparatus embodying a preferred form of the invention. The apparatus described is, however, merely illustrative and it will be understood that our invention embodies any and all of the devices or combinations coming within the scope of the appended claims.

In the drawings which form a part hereof and in which like reference numerals indicate like parts, Fig. 1 is a top view of an apparatus embodying a preferred form of our invention. Fig. 2 is a front view of the same, partly in section. Fig. 3 is a vertical section on the center line of the filter. Fig. 4 is a vertical section on the center line of Fig. 3. Fig. 5 is a vertical section on the longitudinal center line of the still. Fig. 6 is a top view of the still with cover removed. Fig. 7 is vertical section on the line 7—7 of

Fig. 6. Fig. 8 is a diagram of the electrical connections.

The apparatus is preferably mounted on a horizontal pedestal 10 which is rounded at both ends to accomodate the contaminated oil tank 11 and the pure oil tank 12 respectively. An upper horizontal frame member 13 of corresponding form is provided with annular depressions 14, 15 in its lower surface to fit over the upper edges of the tanks 11 and 12. The member 13 consists of a continuous vertical flange 16 and web or drain portion 17, which slopes from the top of the tank 12 to the lip of the tank 11 so that any oil spilled upon it will drain into the tank 11.

The bottom of the tank 11 may converge conically toward a valve 18 communicating with a lower chamber 19 provided with a hand hole 20 for the purpose of removing relatively large solid particles that may be in the oil when it is put in the tank 11. Such impurities together with the oil that is particularly dirty, lumpy, or thick and undesirable, pass by natural settling action into the chamber 19. This can be occasionally cleaned out by closing the valve 18 and opening the hand hole 20.

The pipe 21 carries oil from a point near the bottom of the tank 11 but above the valve 18 to the pump 22 here indicated as an ordinary gear pump operated by the shaft 23, disk 24, friction wheel 25, and electrically operated motor 26. The motor 26 is pivotally supported near one end by brackets 27 so that the wheel 25 is held in friction engagement with the periphery of the disk 24 by a considerable portion of the weight of the motor 26. We find a friction drive or its equivalent is desirable in order to prevent undue pressure or breakage in the pump or filter.

The oil is pumped through pipe 28 into the filter casing 29 entering the casing by a port (see Fig. 4) located preferably in the upper portion of one of the side walls thereof. The filter may be of any desired form or kind. We have shown a filter in which a relatively large filtering area is combined with compactness and efficient filtering means. The filter casing is rectangular in horizontal section with a clean out port 30 at the bottom. The filter cover 31 is provided with a central outlet aperture 32 and is adapted to support in communication therewith a depending hollow T-shaped fitting 33, upon which the filter elements are adapted to be mounted. The filter elements 36 may be of any well-known construction but for compactness we prefer to use metallic drainage elements 35 coated with appropriate filtering material and providing internal drainage space for the passing of filter oil to the filter outlet 32 as hereinafter described.

According to this construction as illustrated in Fig. 4 each filtering element is aper-

tured near the top thereof to fit snugly over one or other of the horizontal arms 34 of the T-shaped fitting 33.

Such filtering elements and their supports are fully described in the co-pending application of G. H. Greenhalgh filed November 27, 1923, Serial No. 677,202. The horizontal arms 34 of the member 33 are adapted to pass through the apertures in the drainage member 35 of each of the several filtering elements 36, and the same are held rigidly in place on the arms 34 by screws 37 engaging interior threads within the arms 34. Longitudinal slots 38 in the members 34 allow communication between the hollow interior of the arms 34 and the interiors of the several drainage elements 35 thus affording passage for the filtered oil from the interior of each drainage member 35 to the interior of the arms 34 of fitting 33. As shown in Fig. 4 the filtered oil then rises through fitting 33 to the filter outlet 32. The drainage elements 35 are preferably covered by filtering material such as canton flannel or the like, which may be impregnated with a filter aid such as keiselguhr, though excellent results are obtainable without the use of such a filter aid. The drainage elements themselves are constructed as a form for the filtering material and to provide free drainage space for the oil after it has passed through the filtering material, and to prevent the filter material under pressure from the pump from clogging the drainage space.

The foregoing construction makes cleaning of the filter very easy by simply removing the filter cover 31 carrying with it the member 33 and all the filter elements 36. The filter elements may be disassembled by unscrewing the screws 37 and assembled again without difficulty.

From the filter outlet 32 the filtered or clarified oil preferably passes under reduced pressure (due to the resistance of the filtering elements 36 to the flow of oil therethrough) to an overflow tank or gravity feed device 40, which in the drawings is shown directly on top of the filter cover 31. It is simply a chamber having an inlet communicating with the outlet 32 from the filter, an outlet 42 at a high level communicating by pipe 43 with the receiving tank 11, and an outlet 44 at a low level communicating by pipe 45 with the still 46. The purpose of this gravity feed device is to make the feed to the still a feed under constant pressure determined by the gravity head of the oil between the outlet 42 and the still 46, and independent of variations in the pressure of oil from the filter. Any excess in the amount of filtered oil over the amount of oil admitted to the still by the automatic feed control device hereinafter described simply overflows through pipe 43 back into the tank 11.

The still 46 consists of an oil chamber 47 separated by a horizontal partition 48 from

a heating chamber 49, wherein is contained any desired form of heating device. We have illustrated an electric heating element because of the ease of controlling the same in connection with the other operating parts of the apparatus. At or near one end of the chamber 47 is a vapor outlet 50 and a pure oil-outlet 51. A flange 52 extends around the upper edge of the walls of the chamber 47. Near the opposite end of the still 46 from the outlets 50 and 51, the flange 52 and walls of the chamber 47 are cut away to receive the parts 53 and 54 of the feed control member 55. A cover 56 is provided for the chamber 47 which fits tightly to the flange 52 and around the upper portions of the parts 53 and 54, so that on both sides and at the outlet end of the still, the cover 56 forms air tight connection with the body of the still. A vent 57 is provided at the inlet end of the still to allow air to pass into the still and over the surface of the hot oil, as hereinafter described.

The feed control device 55 comprises a hollow cylindrical portion within which is closely fitted a sleeve 58. In the lower portion of the part 55 are a number of valve chambers 59, 60, each valve chamber communicating with the hollow cylindrical portion of the part 55, and also having a vertical movable valve 61 and valve stem 62 and spring 63 acting on a pin 64 on the valve stem to keep the valve normally seated in the closed position. The sleeve 58 is provided with a number of apertures 65 disposed helically around its surface so that when the sleeve is rotated to bring one aperture 65 into communication with its corresponding valve chamber, the other apertures are in such position as to close off communication between their corresponding valve chambers and the interior of the sleeve 58. The sleeve 58 communicates through part 53 with pipe 45, by which oil is conveyed to the still from the gravity feed device 40. A handle 66 is attached to part 54 by which to turn the sleeve 58 into desired position. By this means the entering flow of oil through pipe 45 may be put into communication with any one or other of the valve chambers 59, 60, at will by turning the handle 66 and part 54 into proper position to bring one of the apertures 65 into communication with the desired valve chamber.

Arms 67, 68 extend diagonally downward from the feed control member 55 toward the bottom of the chamber 47 at the outlet end. The lower ends of these arms are connected by a cross bar 69 having a lug 70 adapted to rest on a projection 71, which positions the bar 69 in spaced relation above the partition 48. Strips of bi-metallic thermostatic metal 72, 73, corresponding in number to the number of valve chambers 59, 60, are attached at one end to the bar 69 by screws 74 so that they normally lie in horizontal position with

their free ends under the valve stems 62 of the corresponding valve chambers. These thermostatic strips of metal are adapted to lift the corresponding valves at different temperatures, one of them at a relatively low temperature, for example, 400° F., another at a higher temperature, for example 460° F., and another at a still higher temperature, for example, 500° F., etc. Any appropriate form of thermostat may be employed. We have successfully used common bi-metallic strip thermostats where brass was the lower metal and steel the upper metal. It will be understood by those skilled in the art that such a bi-metallic strip, supported as shown in Fig. 5, will bend its free end upward when subjected to increasing temperature because of the difference in coefficient in expansion of brass over steel. The valves 61 and springs 62 are made light and small so as to be easily operated by upward pressure of the thermostats. The pressure of oil on the valves 61 is only such as results from the slight gravity head in device 40. There can be no pressure from pump 22 in the oil line 45 to the still because of the free overflow of excess oil from device 40 by passages 42 and 43 into the container 11. Thus we have found that in our apparatus the lifting force of the thermostats is amply sufficient to operate the valves and to control the flow of oil into the still as described.

The operation of the still 46 is as follows.

The handle 66 is turned to bring one of the apertures 65 into communication with the valve chamber which corresponds to the thermostat by which it is desired to have the flow of oil to the still controlled. For example, if it is desired to produce a relatively thin oil, the thermostat operating at relatively low temperature would be employed. Assuming the strip 72 to be the thermostat operating at relatively low temperature and the valve chamber 59 the one corresponding with that thermostat, the operator would turn handle 66 so that an aperture 65 would be brought into communication with the valve chamber 59, thereby putting the valve chamber 59 into direct communication with pipe 45 through the sleeve 58 and part 53. Upon applying heat in chamber 49 as by passing current through the electric stove illustrated in the drawings, the temperature of the oil in the chamber 47 is raised. As the temperature of the oil rises, the free ends of the thermostats begin to rise; thermostat 72 rising most rapidly because it is set to operate at the lowest temperature; thermostat 73 rising less rapidly because set to operate at a higher temperature, and so on. When the oil reaches the temperature for which thermostat 72 is set to operate, the free end of that thermostat comes in contact with the valve stem 62 of the valve 61 in valve chamber 59, as shown in dotted lines in Fig. 7, and then lifts the valve

61 so that oil from the gravity feed device 40 flowing through pipe 45, sleeve 58, aperture 65, and valve chamber 59, is permitted to flow past the valve 61 into the chamber 47, thereby cooling the oil therein. The cool oil continues to flow into the still in this manner until the temperature of the oil is reduced sufficiently to move the thermostat 72 downward, so that the valve 61 is closed and the inflow of cold oil stopped. This operation is repeated with alternate opening and closing of the valve 61, and the temperature of the oil in the chamber 47 is thereby kept substantially uniform. The vapors formed at this temperature are drawn off through the outlet 50 and the residue oil of desired viscosity may flow out through overflow outlet 51.

If it is desired to produce a medium viscosity oil, the handle 66 and sleeve 58 may be turned to bring an aperture 65 in communication with the valve chamber 60. In this way communication between the sleeve 58 and valve chamber 59 is cut off so that operation of the valve 61 by thermostat 72 is ineffective to allow oil to flow into the still. At this position of the handle 66 the inflow of oil is controlled by thermostat 73, which, in like manner, tends to keep the temperature of the oil in the chamber 47 substantially constant at an intermediate temperature, for example 460° F.

Similarly if the handle 66 is set to allow communication only with the valve chamber corresponding to the thermostat that controls for the highest temperature, the oil in the still will be held substantially uniform at the highest temperature. In short, the thermostats are each effective to open the corresponding valves when the oil in the still reaches the temperature for which they are set, but each one is effective to allow inflow of new oil and thereby control the temperature in the still only when the handle 66 is set to provide communication between pipe 45 and the valve chamber corresponding to that particular thermostat. In this way means is provided for automatically controlling the viscosity of the residual oil produced in the still and for controlling this means to produce oil of relatively low viscosity or high viscosity or of intermediate viscosity. It is only necessary to set the handle 66 to a position corresponding to the viscosity desired and the still automatically produces oil of that viscosity.

In order to promote distillation and to facilitate the collection of the diluents, the apparatus is preferably provided with means for passing a flow of air over the surface of the hot oil in the still. In the device shown in the drawings, this is accomplished by providing the vent or slot 57 between the cover and body portion of the still, and by providing a suction fan between the vapor outlet 50 and the distillate tank 80. A vapor pipe 81 connects the vapor outlet from the still 46 to

the fan housing 82 bolted to the housing of the motor 26. A fan 83 on the shaft of the motor 26 sucks the air and vapors through pipe 81 and drives them through pipe 84 into the distillate tank 80 where the vapors are collected and may be condensed by any appropriate means, not shown. The distillate generally consists of light hydrocarbons, including gasoline, kerosene, etc., which may be of considerable value for use in cleaning tools, burning as fuel, and other purposes.

When the oil in chamber 47 rises to outlet 51, it overflows through pipe 85 into the pure oil tank 12. This oil, having been filtered and then distilled at a temperature controlled and kept uniform by the particular thermostat that is in operation, will be free both of solid impurities and of those diluents that boil at temperatures lower than that maintained in the still. The filtered and distilled oil which collects in the pure oil tank 12 we accordingly refer to herein as reclaimed oil.

At a point near the bottom of the receiving tank 11 but somewhat above the opening into the pipe 21, a float 90 is supported by the arm 91 pivotally attached to the tank wall. A contact 92 is carried by the float 90 and is adapted in one position of the float to engage a second contact 93 and to be out of contact therewith in another position of the float. As shown in Fig. 8, these contacts are connected by suitable wires with a source of electrical energy and with the motor 26 and the electrical heating unit 49^a disposed in the chamber 49 of the still 46. The contacts are brought into engagement with each other at a predetermined oil level but below that level are out of engagement with each other. When the contacts are engaged both the motor 26 and the still 46 are energized but when the contacts are disengaged both the motor and the heating unit of the still are de-energized. By this means the pump, fan and heating unit are energized only when the oil in the tank 11 has reached a predetermined level. At other times the various units are de-energized. The apparatus works automatically upon the introduction of oil into the receiving tank 11.

Accordingly the machine will be seen to be automatic in every particular. It is merely necessary to decide what viscosity of oil is desired and set the handle 66 accordingly, and then introduce used oil into the tank 11. The machine will at once function to effect an initial settling purification of the oil by dropping the heaviest impurities into the chamber 19. The remainder of the oil will be forced by pump 22 under pressure through the filter 29, thereby effectively clarifying the oil and removing fine impurities. The clarified oil will be passed in turn to the still 46 in such quantity as the automatic control mechanism in the still will permit, the balance

of the clarified oil being returned to the tank. By the time the oil in the tank 11 has dropped so low as to open switch 92, the filter and still will have functioned to purify the oil passing through them resulting in the collection of clarified and distilled oil of uniform viscosity in the pure oil tank 12, and the collection of distillates largely consisting of lighter hydrocarbons in the distillate tank 80.

No supervision whatever is necessary as the device stops when it has no further work to do. Thus is provided a simple and efficient device which not only disposes of the used oils, but automatically and cheaply produces and collects in separate vessels pure lubricant of uniform viscosity and distillates of considerable value.

It will be understood that the foregoing description of the invention in connection with the reclamation of used oil is not to be understood as limiting the invention to that use. It may be used for removing contamination from a variety of different liquids. It may be used for clarification or filtration alone, or it may be used for distillation alone, or if desired, an auxiliary filter may be inserted between the still and the tank 12 for removing from the distilled liquid any undesirable products of distillation. While it is generally desirable in the case of oil to distill it after it has been substantially clarified, it may be preferable in certain cases or in the treatment of certain liquids, to reverse the order of treatment and distill before clarifying. A great variety of changes and rearrangement of parts may be made without departing from this invention. The foregoing description and annexed drawings are merely intended to illustrate and not to limit the invention as defined in the appended claims.

Having thus described our invention, what we claim as new and desire to secure by Letters Patent is:—

1. In an apparatus of the character described a tank, a filter, a still, power operated means for transferring liquid from said tank successively to said filter and still and control means for starting and stopping said transfer means, said control means being responsive to a change in level of liquid in said tank.

2. In an apparatus of the character described a tank, a filter, a still, means for heating said still, means for transferring liquid from said tank successively to said filter and still and control means for starting and stopping said transfer and heating means, said control means being responsive to a change in level of liquid in said tank.

3. In an apparatus of the character described a tank, a filter, a pump for transferring liquid from said tank to said filter, a still, a conduit leading from said filter to said still and means responsive to the temper-

ature of the liquid in said still for controlling flow through said conduit.

4. In an apparatus of the character described a tank, a filter, a pump for transferring liquid from said tank to said filter, a still, a conduit leading from said filter to said still, means responsive to the temperature of the liquid in said still for controlling flow through said conduit and means responsive to a change in level of liquid in said tank for starting and stopping the operation of said pump.

5. In a device of the character described a tank, a filter, a pump for transferring liquid from said tank to said filter, a still, means for heating said still, a conduit leading from said filter to said still, means responsive to a change in level of liquid in said tank for controlling said pump and said heating means and means responsive to the temperature of the liquid in said still for controlling flow through said conduit.

6. In an apparatus of the character described a still, a plurality of inlets, valve means for selectively controlling said inlets, a temperature responsive device individual to each inlet for controlling flow therethrough, said devices being operable at different temperatures, a tank, a filter and a pump for transferring liquid from said tank through said filter to said still.

7. In an apparatus of the character described a tank, a filter, a pump for transferring liquid from said tank to said filter, a still, a conduit connecting said filter and still, heating means for said still, a fan for removing vapors from said still and control means for starting and stopping said pump, fan and heating means, said control means being responsive to a change in level of liquid in said tank.

In testimony whereof, we have signed our names to this specification.

GEORGE H. GREENHALGH.

ROBERT P. F. LIDDELL.
